DESIGN FOR A WALL MOUNTED EYEGLASS HOLDER

John S. Schram, Columbus, Ohio

Application July 11, 1938, Serial No. 78,385

Term of patent 7 years

To all whom it may concern:

Be it known that I, John S. Schram, a citizen of the United States, residing at Columbus, in the county of Franklin and State of Ohio, have invented a new, original, and ornamental Design for a Wall Mounted Eyeglass Holder, of which the following is a specification, reference being had to the accompanying drawing, forming a part thereof.

Fig. 1 is a perspective view of a well mounted eyeglass holder, showing my new design;

Fig. 2 is a front elevational view thereof;
Fig. 3 is a side elevational view.

I claim:

The ornamental design for a wall mounted eyeglass holder, as shown.

JOHN S. SCHRAM.
